(57) **CLAIM**

The ornamental design for tee shirt, as shown and described.

DESCRIPTION

FIG. 1 is a front elevational view of the tee shirt, showing my new design;

FIG. 2 is a top plan view thereof;

FIG. 3 is a bottom plan view thereof;

FIG. 4 is a rear elevational view thereof;

FIG. 5 is a left side elevational view thereof, and;

FIG. 6 is a right side elevational view thereof.

The broken lines shown in FIGS. 1, 2 and 4–6 represent stitching.
